UNITED STATES PATENT OFFICE.

ARCH C. SHIRLEY, OF FORT SMITH, ARKANSAS.

ASSEMBLING AND DISASSEMBLING DEVICE.

Application filed December 1, 1924. Serial No. 753,259.

To all whom it may concern:

Be it known that I, ARCH C. SHIRLEY, a citizen of the United States, residing at Fort Smith, in the county of Sebastian and State of Arkansas, have invented new and useful Improvements in Assembling and Disassembling Devices, of which the following is a specification.

The present invention contemplates the provision of means for facilitating the operation of assembling and disassembling parts of the mechanism of an automobile, and aims to provide means of this character which are especially useful in assembling and disassembling the transmission mechanism and the magneto of the type used in Ford automobiles.

To this end, the invention includes means for holding the magneto, transmission mechanism and various parts thereof, so that the different elements may be conveniently supported, removed and reassembled with a minimum amount of time and labor, the invention including a plurality of interchangeable supporting and holding elements of a simple and durable character.

With the above and other objects in view, the invention further includes the following novel features and details of construction, to be hereinafter more fully described, illustrated in the accompanying drawings and pointed out in the appended claims.

In the drawings:—

Figure 1 is a top plan view showing the base of the assembling and disassembling device mounted upon a bench or support, the remainder of the device being removed.

Figure 2 is a vertical central sectional view partly in elevation showing the transmission mechanism and a portion of the magneto of an automobile arranged for removing and installing the magneto magnets, the clutch plates, fly wheel and ring gear.

Figure 3 is a detail plan view of the removable and reversible magnet engaging disk.

Figure 4 is a fragmentary top plan view of the magnets.

Figure 5 is a sectional view partly in elevation showing the mechanism in position for the removal of the transmission from the fly wheel and magneto.

Figure 6 is a reverse plan view of the magnet engaging disk shown in Figure 3.

Figure 7 is an elevation of the brake drum 55 of the automobile mechanism.

Figure 8 is a view similar to Figure 5 with the parts in position for the removal of the transmission drums.

Figure 9 shows the mechanism in position 60 for the removal and installation of the magnets.

Figure 10 is a plan view of the transmission shaft supporting disk.

Figure 11 is a sectional view with the 65 parts in position for assembling the transmission and fly wheel.

Figure 12 is a plan view of one of the drum rings.

Figure 13 is a sectional view with the 70 parts in position for the removal of the bushing of the slow speed drum.

Figure 14 is a reverse plan view of the ring illustrated in Figure 12.

Figure 15 is a view similar to Figure 13 75 with the mechanism arranged for the removal of the bushing of the brake drum.

Figure 16 is a plan view of the triple gear ring.

Figure 17 is a sectional view showing the 80 brake drum ring and triple gear ring arranged for the removal of the bushing of the triple gear.

Figure 18 is a view of the reverse side of the triple gear ring shown in Figure 16. 85

Figure 19 is a view similar to Figure 17 with the triple gear in place.

Figure 20 is a detail perspective view of one of the clutch plate tools.

Referring in detail to the drawings 90 wherein like characters of reference denote corresponding parts, the invention as shown comprises a base 20 which is mounted upon a suitable support, such as a work bench or table 21. This base is provided with an annular boss 22 and a central opening 23, the wall of this opening having an annular shoulder 24 from which extends a pin 25. The purpose of this pin will be presently apparent. 95

The mechanism for which the present invention has been especially designed includes a transmission mechanism, a fly wheel and a magneto, all of which are included in a unitary structure as illustrated in Figure 2 of the drawings. The transmission mechanism includes a brake drum 26, a slow speed drum 27 and a reverse speed drum 28, 100 105

while the transmission shaft is indicated at 29. This shaft carries at one end a flange or disk 30. The transmission mechanism further includes a plurality of triple gears 31.

5 The reference character 32 indicates the clutch plates, 33 the fly wheel, 34 the ring gear which is mounted upon the fly wheel and 35 the magnets of the fly wheel carried 10 magneto, the said magnets being held in place by bolts 36. As previously stated this structure provides a unit which comprises a portion of the mechanism of a Ford automobile and it is not essential to the understanding 15 of the present invention to specifically describe this structure or its operation.

The present invention provides means for conveniently supporting the unit so that access may be had to its various elements for 20 the purpose of removing and installing them and to do this the invention provides the base plate 20 previously mentioned, the boss 22 of which is of a size to fit within the recessed face of the fly wheel 33 so that 25 this face of the wheel may rest upon the boss 22 with the drums 26, 27 and 28 extending downwardly through the opening 23 of the base plate and through an opening 37 provided in the table or bench 21. 30 The entire unit is thus supported upon the base plate in a manner to permit of the said unit being revolved so as to conveniently reach the bolts 36 so that the magnets 35 and ring gear 34 may be conveniently removed 35 from the fly wheel. In addition, the clutch plates may be removed through an opening 38 provided in the table support, the plates being removed by means of a suitable tool, one of which is indicated at 39 in Figure 20 40 of the drawings. It is preferred to employ two of these tools and they are provided at one end with a right angled extension 40 for engagement with the clutch plates 32.

For the purpose of supporting the mechanism 45 in position for the removal of the transmission from the fly wheel there is provided a disk 41 which is illustrated in detail in Figure 3 of the drawings. This disk is of a diameter to fit within the opening 23 of the base 20 and rest upon the annular shoulder 24, the disk being provided with 50 openings 42 which receive the pin 25 and prevent rotation of the disk. The disk 41 is provided with spaced sockets 43 which 55 are arranged concentrically around a central opening 44, these sockets being of a size and number to receive the heads of the bolts 36. The fly wheel is thus held against rotation so that the transmission mechanism may be 60 conveniently removed, the position of the parts being illustrated in Figure 5.

As shown in Figure 6 of the drawings, the disk 41 is provided upon the face opposite that shown in Figure 3 with an annular boss 65 45 and this boss is provided with radially

disposed grooves 46. In order to disassemble the transmission drums after they have been removed from the fly wheel, the disk 41 is positioned within the opening 23 of the base with the boss 45 uppermost. The 70 brake drum 26 which is provided with spaced lugs 47 as shown in Figure 7 of the drawings has these lugs positioned within the grooves 46 so that the drums will be held against rotation for their convenient 75 separation.

For the purpose of removing and installing the magnets of the magneto, the disk 41 is arranged as shown in Figure 5 of the drawings. The fly wheel 33 is then placed 80 upon the base as in Figure 2 of the drawings and the pins 48 of the triple gears 31 which extend downward are received within spaced openings 48' which extend through the disk 41. This arrangement is illustrated 85 in Figure 9 of the drawings.

To reassemble the transmission and fly wheel, the fly wheel and magnets are arranged as shown in Figure 11, the flanged end 30 of the transmission shaft 29 resting 90 upon a centrally located boss 49 provided upon one face of a disk 50. This disk rests upon an annular shoulder 51 which surrounds the opening 44 of the disk 41.

In order to facilitate the removal of the 95 bushings from the drums 26, 27 and 28 there is provided an annulus or ring 51 illustrated in Figures 12, 13 and 14. This annulus is provided upon one face with a marginal 100 flange 52 and is of a diameter to rest upon the seat 53 of the disk 41. The opposite face of the annulus or ring 51' is provided with a relatively wide marginal flange so that the seat 53 is provided for receiving the end flange of the drum sleeve 54. The 105 bushing of this sleeve which is shown at 55 may then be conveniently removed. The drum illustrated in Figure 13 is the slow speed drum 27.

The ring or annulus 51' shown in Figures 110 12, 13 and 14 may be reversed from the position shown in Figure 13 and may receive a ring or annulus 56 of a relatively small diameter. This last mentioned ring or annulus is provided upon its opposite face with 115 marginal flanges 57 which form seats 58, one of these seats being of a diameter to receive the triple gears 59 so that the bushings 60 of the latter may be conveniently removed.

The invention is susceptible of various 120 changes in its form, proportions and minor details of construction and the right is herein reserved to make such changes as properly fall within the scope of the appended 125 claims.

Having described the invention what is claimed is:—

1. Means of the character described comprising a base plate having an opening there- 130

in, a disk fitting within and engaging the walls of the opening and supported by the base plate, said disk having a central opening and spaced sockets in one face thereof around the opening, reversible nested rings having seats in their opposite faces, means providing a removable engagement of the rings within the opening of the disk, a relatively small disk also adapted to be removably supported and engaged by the first mentioned disk and a central boss provided upon one face of the relatively small disk.

2. Means of the character described comprising a base plate having an opening therein, a reversible disk fitting within and engaging the walls of the opening and supported by the base plate, said disk having a central opening and spaced sockets in one face thereof surrounding the opening and spaced openings extending through the disk, an annular flange surrounding the opening upon the opposite face of the disk, said flange having spaced radially disposed grooves therein, reversible nested rings having seats in their opposite faces, means providing a removable engagement of the rings within the opening of the disk, a relatively small disk also adapted to be removably supported and engaged by the first mentioned disk and a central boss provided upon one face of the relatively small disk.

3. Means of the character described comprising a base plate having an opening therein, a reversible disk fitting within and

engaging the walls of the opening and supported by the base plate, said disk having a central opening and spaced sockets in one face thereof surrounding the opening and spaced openings extending through the disk, and an annular flange surrounding the opening upon the opposite face of the disk, said flange having spaced radially disposed grooves therein.

4. An assembling and disassembling device for automobile transmissions and magnetos comprising a base plate provided with a circular boss having an opening therein, said boss being of a diameter to fit within the flange upon one face of the fly wheel of an automobile, a disk removably supported within the opening, said disk also having a central opening therein and means carried by the fly wheel and adapted to engage the disk to hold the fly wheel against rotation.

5. An assembling and disassembling device for automobile transmissions and magnetos comprising a base plate provided with a circular boss having an opening therein, said boss being of a diameter to fit within the flange upon one face of the fly wheel of an automobile, a disk removably supported within the opening, said disk also having a central opening therein and means for locking the fly wheel against rotation.

In testimony whereof I affix my signature.

ARCH C. SHIRLEY.
